UNITED STATES PATENT OFFICE.

HENRY E. BRYANT, OF JACKSONVILLE, FLORIDA.

DESIGN FOR A BOOKCASE.

43,588.

Specification for Design.

Patented Feb. 25, 1913.

Application filed September 23, 1911. Serial No. 651,001. Term of patent 14 years.

To all whom it may concern:

Be it known that I, HENRY E. BRYANT, a citizen of the United States, residing at Jacksonville, in the county of Duval, State of Florida, have invented a certain new, original, and ornamental Design for a Bookcase; and I do hereby declare the following to be a full, clear, and exact description of the invention, such as will enable others skilled in the art to which it appertains to make and use the same.

This invention relates to new and useful improvements in designs for book cases.

In the accompanying drawing the figure is a perspective view of my invention.

The improved book case comprises a base from the central portion of which extends a desk which consists of a removable top below which is located a draw and a receptacle having a hinged draw. A plurality of pigeon holes are arranged above the desk top while extending above the said pigeon

holes is a clock. A plurality of book shelves are arranged upon one side of the desk and are closed by a glass door while upon the opposite side of the book case is located a compartment in which are provided a plurality of hooks to support wearing apparel. A pair of vertically extending arms project from the top of the last mentioned compartment and have pivotally supported therebetween a mirror for the assistance of the user of the cabinet. The book case is mounted upon suitable supports as clearly shown in the drawing.

I claim—

The ornamental design for a book case as shown and described.

In testimony whereof, I affix my signature, in presence of two witnesses.

HENRY E. BRYANT.

Witnesses:

S. R. BRATTAN,
GEO. H. CHANDLER.
